Primary Examiner—W. Stallard

[57] CLAIM

The ornamental design for a handle for compass saw, as shown.

DESCRIPTION

FIG. 1 is a side elevational view of a saw handle employing my new design, with a compass saw blade illustrated in phantom line, the stippling on the handle indicating a roughened surface texture for the grip portion; FIG. 2 is an enlarged side elevational view of the handle;

FIG. 3 is a rear elevational view thereof;

FIG. 4 is a front elevational view thereof;

FIG. 5 is a top plan view thereof; and

FIG. 6 is a bottom view thereof.
